UNITED STATES PATENT OFFICE.

FRANK B. WOOD, OF NEW YORK, N. Y., ASSIGNOR TO THE NEW HAVEN CLOCK COMPANY, OF NEW HAVEN, CONNECTICUT.

TELEGRAPH-REGISTER.

SPECIFICATION forming part of Letters Patent No. 338,329, dated March 23, 1886.

Application filed November 9, 1885. Serial No. 182,213. (No model.)

To all whom it may concern:

Be it known that I, FRANK B. WOOD, a resident of New York city, in the county and State of New York, have invented an Improved Telegraph-Register, of which the following is a full, clear, and exact description, reference being made to the accompanying drawings, in which—

Figure 1 is a side view of my improved telegraph-register. Fig. 2 is an enlarged side view, partly in section, of a portion of the same. Fig. 3 is an enlarged end elevation of the same, and Fig. 4 is an enlarged inner face view of one of the end plates thereof.

The object of this invention is to improve telegraph-registers which are employed to mark dots and dashes and other figures upon strips of paper that are fed through them, with the view of preventing the marking-tool from sticking in the paper, simplifying the construction of the parts, and facilitating their repair.

The invention consists, first, in the employment of a cutting-roller in the place of a cutting-pin for marking the paper where the same is in contact with another roller; second, in providing the apparatus with a slide to which the electro-magnets, the armature, the binding-posts, and the electrical conductors are secured, and which slide can readily be removed from the remainder of the instrument for inspection and repair; and, finally, the invention consists in providing said sliding portion with a non-conducting plate, in which the binding-posts and the ends of the conductors are secured, all as hereinafter more fully described.

In the accompanying drawings, the letter A represents the box or case of the telegraph-register. The same supports the paper-reel B and the rollers C and D, between which rollers the paper passes, and by which it is fed along—that is to say, the roller D is revolved by clock-work and the paper J crowded against it; hence the roller D in reality moves the paper, and this in turn the friction-roller C. The tight grip which both rollers have on the paper causes it to be fed along in the manner just described. The box A is closed at one end by a vertical plate, E, which

at the upper end has a horizontal attachment, F. (See dotted lines in Fig. 1, and full lines, Fig. 2.) This horizontal portion F, which is rigidly attached to the upright plate E, constitutes a cover to all that part of the box A which lies behind the roller D. The edges of the horizontal plate F are tongued, as at a in Fig. 4, to enter the grooved sides b b of the box A, and into these grooved supports the cover portion F can be slid, carrying with it, when moved, the upright end plate, E. Thus the angular part E F is removable from the remainder of the box A, so as to lay bare the internal mechanism—that is to say, the clock-work part that is contained within said box— whenever said angular part is taken out. To this removable portion E F are also secured, on the inner side thereof, the electro-magnets G, while on the outer side thereof is pivoted at d the armature-lever H, which carries the marking or pricking tool e. To the removable part E F are also secured the binding-posts I I, to which the electrical conductors f g are connected; hence by removing the angular part E F the internal mechanism of the box is not only laid bare, as heretofore stated, but the electrical mechanism is also removed and laid bare for examination and repair.

The armature-lever H, which, as before stated, carries the pricking-tool e, has in all prior instruments of this kind which are in use been provided with a pin for pricking or marking the paper J. According to my invention, however, the instrument e is a cutting-roller hung in the end of the armature-lever H and adapted to groove or cut the paper when crowded against it with its continuous sharp or V-shaped cutting-edge. The roller e is so located that it touches the paper on the roller C. The principal advantage of this arrangement is, that the tool which cuts or grooves the paper cannot stick therein, and that consequently it will offer no resistance to the proper continuity of the action of the apparatus, the roller e crowding the paper against the roller C, and afterward revolving by contact with the same.

A portion of the upright plate E is made non-conducting. This non-conducting por-

tion is shown at L in the drawings, and is, by preference, a plate made of suitable well-known non-conducting substance set into an aperture of the plate E. In this non-conducting portion L are secured the several binding-posts I and switches for regulating the course of the currents on the conductors. This arrangement enables me, in the first place, to have the electrical connections well in hand without requiring the whole box A to be lifted up. In the older contrivances known to me the conductors were carried under the bottom of the box A and there joined to binding-posts, which arrangement required the upsetting of the entire box in order to get at these connections. It is evident that by setting this non-conducting plate L into the removable angular end piece, E F, of the box opportunity for ready inspection and repair is greatly increased.

The lever H may carry one marking-roller e or more than one. Two such levers are shown in Fig. 4 of the drawings.

I do not claim printing-rollers that are carried on armature-levers for printing ink on paper.

I claim—

1. In a telegraph-register, the armature-lever H and the roller e, which is carried by said armature-lever, in combination with the roller C, and means, substantially as described, for revolving said roller C by contact with the paper J, the roller e pressing the paper against the revolving roller C in marking the same, substantially as herein shown and described.

2. In a telegraph-register, the main box A, which contains the clock-work mechanism, combined with the sliding end plate, E, having part of the cover F rigidly attached to it, and also with the electro-magnets and armature-lever which it carries, as specified.

3. In a telegraph-register, the combination of the box A with the removable angular slide E F, and with the non-conducting plate L contained therein, and with the binding-posts secured to said non-conducting plate, as specified.

FRANK B. WOOD.
